Primary Examiner — Kelley Donnelly(74) *Attorney, Agent, or Firm* — Foley & Lardner LLP(57) **CLAIM**

I claim the ornamental design for a food and beverage plate, as shown and described.

DESCRIPTION

FIG. 1 is a front perspective view from above of the claimed design including a beverage container as unclaimed background, according to one embodiment;

FIG. 2 is a front perspective view of the claimed design of FIG. 1;

FIG. 3 is a bottom perspective view of the claimed design of FIG. 1;

FIG. 4 is a top view of the claimed design of FIG. 1;

FIG. 5 is a bottom view of the claimed design of FIG. 1;

FIG. 6 is a front view of the claimed design of FIG. 1, wherein the left, right, and rear views are identical to the front view; and,

FIG. 7 is a section view of the claimed design along line 7-7 of FIG. 5.

The broken lines in the drawings are for illustrative purposes only and form no part of the claimed design.
